UNITED STATES PATENT OFFICE

115,116

DESIGN FOR A CABINET FOR CIRCULATING HEATERS

John D. Kaiser, Lansing, Mich., assignor to Motor Wheel Corporation, Lansing, Mich., a corporation of Michigan

Application March 22, 1939, Serial No. 83,769

Term of patent 14 years

To all whom it may concern:

Be it known that I, John D. Kaiser, a citizen of the United States, residing at Lansing, in the county of Ingham and State of Michigan, have invented a new, original, and ornamental Design for a Cabinet for Circulating Heater, of which the following is a specification, reference being had to the accompanying drawing, forming a part thereof.

In the drawing, the single figure is a perspective view of a cabinet for circulating heater

embodying my new design. The horizontal lines extending partially around the top and bottom of the cabinet illustrate stripes of a color which contrasts with the color of the cabinet. The back of the cabinet is plain. The opposite sides are alike.

I claim:

The ornamental design for a cabinet for circulating heater, as shown and described.

JOHN D. KAISER.
